COLOR STRIPING DEVICE

BACKGROUND OF THE INVENTION

1. Field of the Invention

The invention is in the field of marking where it is desirable to identify individual wires or strands by color in order that a number of circuits can be produced and maintained.

2. Background of the Prior Art

Heretofore color coding or striping devices have been expensive, complicated, time consuming, and required particular skill in the use and maintenance of the same, and were beyond the reach of the smaller user or operator.

SUMMARY AND OBJECTS OF THE INVENTION

The present invention includes wire or strand supporting, guiding, and advancing mechanisms, in combination with rotatable color applying mechanism, including pulleys and tensioning mechanism to produce the proper or desired results. Also the wire advancing mechanism, with the necessary pulleys for maintaining the proper tension and alignment of the parts, is utilized to drive or rotate the color carrying mechanism.

It is the object of the invention to provide a simple, practical, easily operated, and efficient wire or strand striping apparatus, inexpensive to produce, operate and maintain, by which a wire or strand is advanced past a particular location where color carrying mechanism is rotatably mounted and of a construction to apply a helical stripe of one or more colors to the exterior of wires or strands for identification purposes.

Other objects and advantages of the invention will be apparent from the following description considered in connection with the accompanying drawings.

BRIEF DESCRIPTION OF THE DRAWINGS

FIG. 1 is a top plan view illustrating one application of the invention;

FIG. 2, a side elevation;

FIG. 3, a front elevation;

FIG. 4, a vertical section on the line 4-4 of FIG. 1;

FIG. 5, a fragmentary detail perspective of a segment of wire or strand striped;

FIG. 6, a plan view of a modified form;

FIG. 7, a front elevation of the embodiment of FIG. 6;

FIG. 8, a side elevation of the embodiment of FIG. 6;

FIG. 9, a rear elevation thereof; and

FIG. 10, a modification with three color stripe containers.

DESCRIPTION OF THE PREFERRED EMBODIMENTS

Apparatus for applying a helical color strip or coding to an electrical conductor wire, or a strand of the same or other substance, in accordance with the movement thereof and of the wire or strand. This apparatus includes a base or platform 10, on which is mounted an auxiliary base or platform 11, carried by supports 12'. Upon the auxiliary base or platform 11 there are adjustably mounted a series of stub shafts 12, 13 and 14 on which are carried supports or guide rollers 15, 16 and 17. About these guide rollers a conductor wire or strand 18 to be striped or coded is wound and in order to maintain desired tension thereon an adjustable tension member 19 is mounted by means of a pin 20 movable in a slot 21.

The conductor wire or strand 18 is looped around rollers 15, 16 and 17, and then around a grooved hub 22 from whence it is extruded centrally through a color carrying wheel or disc 23. The grooved hub 22 is mounted in a pillow block or bearing 24, on the auxiliary platform 11, and the conductor wire or strand encircles the grooved hub 22 and is extended through an axial or central opening 25 in the disc 23 from which the wire or strand passes about a winding spool or other mechanism of conventional character (not shown).

In order to apply color to the conductor wire or strand 18 after it passes through the disc 23, one or more color containing tubes 26 are mounted radially on the disc 23 by means of

retaining clips 27 secured by fasteners to the disc 23. The color tubes 26, which are of conventional character and can be purchased on the open market, include wicks or other color applicators 28 which are intended to be maintained in contact with the wire or strand 18 as it is drawn through the central opening 25 of the disc 23. In order to insure that this result is accomplished a backup plate 29 is provided adjustable relative to the disc 23 by means of a screw 30' located in a slot 31. The front end of the backup plate is of material that will not scratch or mar the wire or strand.

When used in the manner described the rotation of the disc or wheel 23 will cause the color tubes to be repeatedly inverted and insure coloring matter reaching the wicks or applicators, thus applying the stripe 18' to the strand of wire or other substance.

In the embodiment illustrated in FIGS. 6 through 9, a somewhat simpler structure is disclosed. This includes the wire or strand 18 fed around a grooved pulley 33 fixed to a shaft 34, supported by bearings 35 carried by brackets 36 on the base 37. The wire or strand 18 passes through an opening 38 in the guide bearing 39 of the color carrying disc 40 supported by the base 37. The guide bearing 39 at its opposite end has opposed slots 41 in which the wicks 28 of the color tubes 26 are located. The color tubes are mounted by means of clips 27 as previously described. Thus colors are supplied to the wicks 28 which engage the wires or strands as the disc carry the color tubes 26 is rotated.

The color tube carrying disc is rotated by means of a drive wheel 42 adjustably secured along the shaft 34 by means of a setscrew 43. The drive wheel 42 preferably is provided with a resilient frictional peripheral surface 44 for maintaining a positive connection with the color tube carrying disc 40, and this drive wheel 42 may be adjusted lengthwise along the shaft 34, in a cutout opening 37', towards and from the center of the disc 40 for driving or rotating the disc at varying speeds. This varying of the speed of rotation of the color tube carrying disc 40 from the center of the drive wheel 42 serves to vary the spacing of the striping 18' about the wire or strand 18.

In the operation of the device tension is applied and maintained on the conductor wire or strand as it is pulled through the mechanism in order to insure a positive drive and uniformity of the striping. This tension is exerted on the wire or strand through the entire mechanism by the winding of the wire or strand after it has passed through the device, and such tension of the wire or strand is accomplished by winding the wire or strand on a spool of conventional character (not shown).

It will be apparent from the foregoing that while two color tubes are illustrated, one or more may be employed, and in FIG. 10 a supporting disc 46 is provided with three equally spaced retaining clips 27 about a hub 47 having three slots 48 and receiving the wicks 28 in proper alignment and in contact with the wire or strand 18.

It will be apparent that by reversing the winding of the wire or strand about the drive pulley, the color tube carrying disc can be made to revolve in the reverse direction and apply the color striping in the reverse winding.

I claim:

1. Apparatus for applying striping about an elongated flexible member to facilitate identification, said apparatus comprising a base, a relatively thin disc rotatably mounted on said base, said disc having a central aperture through which said elongated member is adapted to be drawn, color applying means removably mounted on one surface of said disc, said color applying means having applicator means positioned contiguous to the aperture for engagement with the elongated member, driving means located adjacent the other surface of said disc and operatively connected thereto, said driving means including pulley means mounted substantially in line with the aperture of said disc and engageable with said elongated member, said pulley being fixed on a shaft the axis of which is substantially transverse to the axis of said disc, and a drive wheel mounted on said shaft and engaging the other sur-

face of said disc for producing rotation of the disc as the elongated member is drawn through the aperture.

2. The structure of claim 1 in which the drive wheel is ad-

justably mounted on said shaft so that the disc can be operated at varying speeds.
